TOY BOAT PROPULSION MEANS

Jan Okonski, 1234 E. Borchard Ave., Santa Ana, Calif.
Filed June 20, 1962, Ser. No. 203,808

2 Claims. (Cl. 46—95)

This invention relates to propulsion means and more specifically to such means particularly adapted for use in propulsion of toy boats.

It is an object of this invention to provide an improved propulsion means.

Another object of this invention is to provide a propulsion means which is inexpensive to produce.

A further object of this invention is to provide a light weight simple propulsion means particularly adapted for toy boats.

Still another object of this invention is to provide an easily operated means for propelling vessels in water.

A still further object of this invention is to provide a toy boat with remotely operated propulsion means.

Other and further objects of this invention will become apparent in the detail description below in conjunction with the attached drawings wherein:

FIGURE 1 is a pictorial view of a toy boat incorporating a preferred form of my invention;

FIGURE 2 is an enlarged cross-sectional view of the rear portion of the boat taken along 2—2 in FIGURE 1;

FIGURE 3 is an enlarged cross-sectional view of the rear portion of the boat; and,

FIGURE 4 is a fragmentary view of the rear end of the boat taken along 4—4 in FIGURE 3.

As will be developed, the present invention includes a novel means for propelling fluid such as water through a port. The velocity given the fluid is useful to move the fluid from one point to another. Also the reaction force which naturally accompanies such acceleration of the fluid may be used in much the same manner as jet aircraft are propelled.

The present invention is particularly well suited to be used as propulsion means for a toy boat. Broadly the propulsion unit comprises a propulsion, or pump, chamber which accomplishes its intended function by the action of a diaphragm chamber operatively associated therewith. As a result of the operation of the diaphragm chamber, water is intermittently discharged from the pump chamber at a relatively high velocity whereupon the reaction forces accompanying this expulsion moves or propels the boat.

Referring now to the FIGURE 1, there is shown a toy boat, indicated generally by the arrow 6, having a hull 7. Disposed at the rear portion of the hull 7 is an elongated housing 8 which extends parallel to the longitudinal axis of the boat 6.

The housing 8 provides a cavity 9 (see FIGURE 2) which receives a propulsion unit according to the present invention. This propulsion unit is operated by fluctuating air pressure in a diaphragm chamber in a manner which will be described in more detail below. In order to supply this fluctuating air pressure, a relatively long flexible tube 11, e.g., three feet long, is connected to rear end of the boat and at its far end carries a hollow semi-rigid squeeze bulb 12 which is adapted to be held in the operator's hand.

Referring now to FIGURES 2 and 4 the propulsion unit will be described in more detail. At the forward end of the cavity 9, the housing 8 has been counterbored to form a seat 13. Also formed at the forward end of the housing 8 is a fitting 14 through which extends passage 15. The fitting 14 receives thereon one end of a short tube 16 which has the other end thereof received on connector 17 secured to the rear of the hull 7. As can be seen, the relatively long flexible tube 11 is also received on the connector 17.

2

Located within the cavity 9 is a rigid cylinder or pump chamber 18 having in end 19 a discharge port or hole 20. Disposed within the cylinder 18 is a flexible diaphragm 21 which is very similar in shape to an elongated balloon.

5 The manner in which the flexible diaphragm 21 and the cylinder 18 are secured to the boat hull 7 should be noted. Forward end 22 of the diaphragm 21 has been turned back over the outside of forward end 23 of the cylinder 18. With this arrangement, by proper sizing of the cylinder 18 relative to the seat 13, the cylinder and the diaphragm 21 may be secured by forcing the forward ends of these elements into the seat 13.

10 With the components arranged as disclosed, there is provided a pump chamber 24 formed between the cylinder 18 and the diaphragm 21. In addition, there is a diaphragm chamber 25 formed between the forward end of the housing 8 in the diaphragm 21.

15 The toy boat 6 is propelled by repeatedly drawing water through the discharge port 20 into the pump chamber 24 and then rapidly expelling that water through said discharge port as indicated by arrows 27 in FIGURE 3. In order to accomplish this the flexible diaphragm 21 is repeatedly moved between the collapsed condition shown in FIGURE 2 in the expanded, or inflated, condition shown in FIGURE 3.

20 The diaphragm 21 is put in the collapsed position in the following described manner. The operator removes the tube 11 from the connector 17. At that time he collapses squeeze bulb 12 substantially. Then he replaces the tube 11 on the connector 17 and releases the bulb 12. As is conventional, the walls of the bulb 12 tend to return to their normal molded position. This draws a partial vacuum, removing the air from the diaphragm chamber 25 whereupon the water pressure collapses the diaphragm.

25 The just described process would not be necessary if the diaphragm 21 were molded in the collapsed condition since the diaphragm would be collapsed before the bulb 12 and the tubes 11 and 16 were connected. However, I prefer to use cylinder diaphragms with one end closed, such as illustrated. These diaphragms are cheaper and also they can be expanded more in the cylinder 18 without undue forces. This permits the operator to discharge water through port 20 more easily and more rapidly.

30 In operation, the operator merely repeatedly squeezes and releases the bulb 12. This action repeatedly varies the pressure in the diaphragm chamber 25 between a partial vacuum and a pressurized condition. The pressure in diaphragm chamber 25 produced by the squeezing of the bulb 12, expands the diaphragm chamber and expels water from the pump chamber 24 by reducing the volume of the latter chamber. This expulsion of the water rearwardly through the opening 20 gives the boat a forward thrust. When the bulb 12 is released, the resiliency of the walls of the bulb cause it to expand effecting a partial 35 vacuum in the diaphragm chamber 25 whereupon water re-enters the pump chamber 24 as the diaphragm chamber contracts.

35 As the boat 6 moves through the water by the propulsion forces above mentioned, the operator follows the boat to maintain slack in the flexible tube 11. Thereby the fact that the tube 11 connects the boat with the hand held bulb 12 does not affect the movement of the boat.

40 While only one embodiment of the present invention has been shown and described in detail, it will be apparent to those skilled in the art that such is by way of illustration only. Numerous changes may be made to the embodiment disclosed without departing from the spirit of the invention.

45 For example, the means which form the pump chamber 24, could be molded as an integral part of the hull 7 of the boat.

50 Similarly the particular shape that the diaphragm means

takes may be changed and still accomplish its intended function.

Accordingly, the scope of this invention should be limited solely to the scope of the appended claims.

I claim:

1. A toy boat adapted to float in the water, said boat comprising:
  - a hull having a predetermined water line;
  - means forming a rigid pump chamber in said boat;
  - means forming a discharge port through which water in said pump chamber may be directed out thereof rearwardly with respect to said boat substantially parallel to said water line, said discharge port being located below said water line;
  - means forming a flexible diaphragm chamber within said pump chamber forming means;
  - hand operated means supplying varying pressure; and a long relatively flexible tube communicating with said diaphragm chamber the pressure of said last mentioned means, whereby operation of said varying pressure means from a point remote from said boat causes said diaphragm chamber to expand and contract causing water to be intermittently expelled from the pump chamber through said discharge port and said boat is propelled along the surface of the water.
2. A toy boat adapted to float in water comprising:
  - a hull having an elongated cavity opening to the rear end thereof;
  - an annular seat formed in the forward end of said cavity;
  - an elongated rigid cylinder in said cavity having an open forward end received into said seat;
  - means forming a discharge port at the rear end of said

cylinder communicating the interior and exterior of the cylinder, said port being below the water level when the boat is floating in water, said port being shaped so as to direct water exiting said cylinder substantially parallel to the surface of the water when the boat is floating in water;

- a resilient diaphragm located within said cylinder and being held between said seat and said cylinder, said diaphragm forming with said seat an expandable diaphragm chamber within said cylinder at said forward end of said rigid cylinder; means for providing partial vacuum and pressure alternately to said diaphragm chamber to contract and expand it;
- a relatively long flexible tube communicating the interior of said diaphragm chamber with the alternating partial vacuum and pressure of said last mentioned means, said tube opening into said chamber through the center of said seat whereby the alternating partial vacuum and pressure contracts and expands said diaphragm chamber and intermittently expels water through said discharge port to propel said boat.
